COOLING SYSTEM FOR MOTORS

Williams G. Milligan, Akron, Ohio

Application April 8, 1933, Serial No. 665,060

15 Claims. (Cl. 123—174)

This invention relates to water-cooling and like cooling systems for motors such as automobile motors.

Heretofore, water-cooling systems for motors required frequent replenishing with water due to losses by evaporation and in the winter when alcohol and like anti-freezing liquid of an expensive nature are used, these losses not only are annoying but are expensive.

10 The general purpose of the present invention is to provide an effective sealed water-cooling system for automobiles to overcome the disadvantages mentioned in the preceding paragraph.

15 More particularly the invention has for an object the association with the standard radiator of a water-cooling system of an auxiliary or condenser radiator condensing any evaporated water or other liquid together with means for returning the condensed vapor back into the liquid or fluid of the cooling system.

20 Another object of the invention is to associate effectively with a system described in the preceding paragraphs, an expansion tank to take care of variations in the pressure in the cooling system. An indicator may be associated with the expansion tank to show excessive pressures due to overheating of the motor as from lack of oil, etc.

25 Another object of the invention is to provide an effective thermostatically controlled by-pass in the water-cooling system to cause the motor quickly to reach its normal operating temperature.

30 The foregoing and other purposes or objects of the invention are attained in the apparatus illustrated in the accompanying drawings and described below. It is to be understood that the invention is not limited to the specific form thereof shown and described.

35 Of the accompanying drawings,

Figure 1 is a side elevation, partly in section, of a water-cooling system embodying the invention shown installed in a motor vehicle;

Figure 2 is a section on line 2—2 of Figure 1;

40 Figure 3 is an enlarged detail of the relief valve as shown in Figure 1;

45 Figure 4 is an enlarged detail of the valve mechanism controlling the flow of the cooling medium as shown in Figure 1 (motor is cold); and

50 Figure 5 is a similar view of the mechanism when the motor is operating at a normal running temperature.

55 Referring to the drawings, the numeral 10 designates an internal combustion engine of a known

type provided with jacketed walls through which a cooling medium is circulated in the usual way. The outlet duct from the motor 10 is shown at 11 and the inlet at 12. The outlet is connected to the top of a radiator in which the water may rise to the level 15 when the system is filled through a filler duct 16 closed by a removable cap 17.

The bottom of radiator 13 is connected through a duct 18 and valve 19 with the intake 20^a of a pump 20 which may be driven by the motor through a shaft 21 and which may discharge at 12 into the water jackets of the motor. Valve 19 preferably has a small hole 19^a through the same to equalize pressure on opposite sides of the valve whereby it will operate easily under any circumstances.

Associated with the radiator 13 is a condenser radiator 22, the top of which at 22^a opens above the level 15 in radiator 13 and accordingly will receive only vapor forming in the system above the level 15 and operable to condense said vapor. The tops of radiators 13 and 22 open into a casing 23 defining an expansion tank and having a flexible diaphragm 24 comprising one wall thereof, there being a relief valve 25 to be described opening to excessive internal pressure or vacuum in the system.

An arm 26 may rest on diaphragm 24 and may be secured to a shaft 27 journaled on casing 23 and having an indicator 28 thereon, the position of which would indicate the pressure in the system and indicating excessive pressure due to motor trouble causing overheating as from lack of sufficient lubricant.

The bottom of radiator 22 is connected through a check valve 29 with a duct 30 which is connected through a valve 31 to the pump intake 20^a or some suitable part of the water-circulating system. The bottom of the radiator 22 may also be connected by a duct 32 through an auxiliary pump 33 driven in any suitable way and arranged to deliver the condensed water from radiator 22 to some part of the water-circulating system such as the main pump intake 20^a.

A by-pass duct 34 preferably connects the outlet 11 through a thermostatic valve 35 and duct 30 and valve 31 to the pump intake 20^a. The thermostatic valve 35 is responsive to the temperature of the water by-passed through duct 34 to close the same when the water reaches a normal motor operating temperature and in some measure through the walls of the various ducts is responsive to the temperature of the water in duct 18. The effect of the water in duct 18 on

the thermostatic valve could be increased by extending the expandible capsule of the valve down into duct 18 if desired.

5 A float 36 is arranged in duct 30 on an arm 37 pivoted at 38 on a lever 39 pivoted at 40 and having a lug 41 thereon for engaging and opening valve 31 and also a link 42 thereon for operatively connecting lever 39 with valve 19. Lever 39 is arranged to be snapped and held in 10 either of the two positions thereof shown respectively in Figures 4 and 5 by so associating a spring 43 with the lever as to yieldingly urge the lever in either direction away from a "dead center." The float arm 37 has an enlarged portion 37^a adjacent its pivot for contacting the side of lever 39 to actuate said lever in one direction or the other as the float is rising or falling.

20 As shown in Figure 3, the relief valve 25 may comprise a pair of valve members 25^a and 25^b cooperating respectively with valve openings 25^c and 25^d, valve member 25^b having openings 25^e therein communicating with openings 25^c permitting internal pressure to affect valve member 25^a, the valve members being held clamped over their respective valve apertures by extending a rod 25^f with an enlarged head 25^g on one end and a spring 25^h between a washer 25ⁱ secured on the other end and one of the valve members.

30 In operation, when the motor is started, when colder than efficient operating temperature, control valves will be set as shown in Figure 4 and the water will circulate through the motor jackets from the pump discharge 12 through the outlet 11 and by-pass 34, past the thermostatic valve 35, through duct 30, and past valve 31 to the 35 pump intake.

When this water reaches the desired operating temperature, as determined by the setting of the thermostatic valve 35, this valve closes whereupon duct 30 is drained by the pump 20 causing the float 36 to fall whereupon valve 31 closes and valve 19 is opened. Thereupon the water circulates from the pump discharge or jacket inlet 12 through the motor jackets to outlet 11 through 45 radiator 13 to duct 18 through valve 19 to the intake 20^a of pump 20.

Any vapor forming in the system passes into radiator 22 and is cooled or condensed therein. The condensate may be drained into the water-circulating system through check valve 29, duct 30 and valve 31 which will operate as a check valve as shown in Figure 5, or the condensate may be withdrawn from the bottom of radiator 22 by the auxiliary pump 33 through duct 32 and 55 delivered into the water-circulating system at any suitable place as at the intake 20^a of the main pump 20.

Modifications of the invention may be resorted to without departing from the spirit thereof or 60 the scope of the appended claims.

What is claimed is:—

1. In combination with a jacketed motor, a normally sealed fluid circulating system, including a fluid cooling radiator, means for circulating the fluid through said jacket and radiator, means for receiving and condensing vapor formed in said system, and means for returning the condensate to the circulating fluid comprising valve means actuated by the condensate for interrupting the fluid circulation through said jacket and radiator and to permit the return of the condensate to the circulating fluid.

2. In combination with a jacketed motor, a normally sealed fluid circulating system, including a fluid cooling radiator, means for circulat-

ing the fluid through said jacket and radiator, means for receiving and condensing vapor formed in said system, and means for returning the condensate to the circulating fluid comprising a snap-action valve means actuated by the condensate for interrupting the fluid circulation through said jacket and radiator and to permit the return of the condensate to the circulating fluid.

3. In combination with a jacketed motor, a normally sealed fluid circulating system, including a fluid cooling radiator, means for circulating the fluid through said jacket and radiator, means for receiving and condensing vapor formed in said system, and means for returning the condensate to the circulating fluid at a location ahead of said jacket comprising valve means actuated by the condensate for interrupting the fluid circulation through said jacket and radiator and to permit the return of the condensate to the circulating fluid.

4. In combination with a jacketed motor, a normally sealed fluid circulating system, including a fluid cooling radiator, means for circulating the fluid through said jacket and radiator, means for receiving and condensing vapor formed in said system, means operatively connected in said system and actuated by pressure developed therein to compensate for expansion and contraction thereby preventing the escape of fluid from said system or the collapse thereof, and means for forcibly returning the condensate to the circulating fluid at a location ahead of said jacket.

5. In combination with a jacketed motor, a normally sealed fluid circulating system, including a fluid cooling radiator, means for circulating the fluid through said jacket and radiator, means for receiving and condensing vapor formed in said system, means operatively connected in said system and actuated by pressure developed therein to compensate for expansion thereby preventing the escape of fluid from said system, and means for forcibly returning the condensate to the circulating fluid at a location ahead of said jacket.

6. In combination with a jacketed motor, a circulating system having a volatile fluid therein including a fluid cooling radiator, means for forcibly circulating the fluid through said jacket and cooling radiator, a condensing radiator for receiving and condensing vapor formed in said system, the inlet thereto being above the normal fluid level in said cooling radiator, means for forcibly withdrawing the condensate from the lower portion of said condensing radiator and returning it to the circulating fluid at a location ahead of said jacket and means operatively connected in said system to compensate for variations of pressure in said system thereby preventing the escape of fluid from said system.

7. In combination with a jacketed motor, a normally sealed fluid cooling system, including a fluid cooling radiator, means for circulating the fluid through said jacket and radiator, means for receiving and condensing vapor formed in said system, means for returning the condensate into the circulating fluid at a location ahead of the jacket inlet, and a flexible member operatively connected in said system and actuated by pressure above normal developed therein to compensate for expansion due to overheating thereby preventing the escape of fluid from the system.

8. In combination with a jacketed motor, a normally sealed fluid cooling system, including a

fluid cooling radiator, means for circulating the fluid through said jacket and radiator, a second radiator for receiving and condensing the vapor formed in said system, means for returning the condensate into the circulating fluid at a location ahead of the jacket inlet, and a flexible member operatively connected in said system and actuated by pressure above normal developed therein to compensate for expansion due to overheating thereby preventing the escape of fluid from the system.

9. In combination with a jacketed motor, a normally sealed fluid cooling system, including a fluid cooling radiator, means for circulating the fluid through said jacket and radiator, means for receiving and condensing vapor formed in said system, means for returning the condensate into the circulating fluid at a location ahead of the jacket inlet, and means operatively connected in said system and actuated by pressure above normal developed therein to compensate for expansion due to overheating thereby preventing the escape of fluid from the system.

10. In combination with a jacketed motor, a normally sealed fluid cooling system, including a fluid cooling radiator, means for forcibly circulating the fluid through said jacket and radiator, means for receiving and condensing vapor formed in said system, means for forcibly returning the condensate to the circulating fluid independently of said fluid circulating means, and means operatively connected in said system and actuated by pressure above normal developed therein to compensate for expansion due to overheating thereby preventing the escape of fluid from the system.

11. In combination with a jacketed motor, a normally sealed fluid cooling system, including a fluid cooling radiator, means for circulating the fluid through said jacket and radiator, means for receiving and condensing vapor formed in said system, means for returning the condensate into the circulating fluid at a location ahead of the jacket inlet, and flexible means operatively connected in said system and actuated by variations of pressure developed therein to compensate for expansion and contraction which takes place within said system thereby preventing loss of fluid or collapse of the system.

12. In combination with a jacketed motor, a normally sealed fluid cooling system, including a fluid cooling radiator, means for circulating the fluid through said jacket and radiator, a by-pass

for shunting a portion of the fluid about the radiator, a thermostatic valve for controlling the flow of fluid through said by-pass, means for receiving and condensing vapor formed in said system, means for returning the condensate into the circulating fluid at a location ahead of the jacket inlet, and a flexible member operatively connected in said system and actuated by pressure above normal developed therein to compensate for expansion due to overheating thereby preventing the escape of fluid from the system.

13. In combination with a jacketed motor, a normally sealed fluid cooling system, including a fluid cooling radiator, means for circulating the fluid through said jacket and radiator, means for receiving and condensing vapor formed in said system, means for returning the condensate into the circulating fluid, and means operatively connected in said system and actuated by pressure developed therein to compensate for expansion due to overheating thereby preventing the escape of fluid from said system.

14. In combination with a jacketed motor, a normally sealed fluid cooling system including a cooling fluid radiator, means for circulating the fluid through said jacket and radiator, means for receiving and condensing vapor formed in said system, means for returning the condensate into the circulating fluid, and means operatively connected in said system and responsive to variations of pressure developed therein to compensate for expansion and contraction thereby preventing escape of fluid from said system or collapse of the system.

15. In combination with a jacketed motor, a normally sealed fluid cooling system including a cooling fluid radiator, means for circulating the fluid through said jacket and radiator, means for receiving and condensing vapor formed in said system, means for returning the condensate into the circulating fluid, yielding means operatively connected in said system and actuated by variations of pressure to compensate for expansion and contraction which takes place within said system thereby normally preventing loss of fluid or collapse of the system, and normally inoperative means in said system actuated by excessive pressure above normal to permit the relief of excessive fluid to atmosphere or below normal to admit air into the system from the atmosphere.

WILLIAMS G. MILLIGAN.
